UNITED STATES PATENT OFFICE.

FRED LAWRENCE HAYES, OF PORT WASHINGTON, NEW YORK, ASSIGNOR, BY MESNE ASSIGNMENTS, TO CHARLES HENRY BICKELL, OF PASSAIC, NEW JERSEY.

TANK TRUCK.

Application filed May 7, 1928. Serial No. 637,045.

The invention relates to tank trucks for transporting and delivering inflammable liquids such as oil and gasoline, in the operation of which heretofore there has been considerable fire hazard resulting from leakage, spilling and collision. The ordinary type of oil tank truck has a tank provided with a bottom outlet, (if there are separate compartments, each compartment has a separate outlet), and pipes extend from the outlets, beneath the tank, to the rear of the vehicle, where they terminate in faucets, from which the liquid is drawn off by gravity into buckets or through hose to storage containers. In order to safeguard the outlets, emergency valves are commonly provided, which are operated either individually from the top of the tank or collectively by some control mechanism.

In spite of the safety features that have been devised for these vehicle tanks, they are deemed unsafe by some city authorities, and where this has been the case they have been forbidden to operate and deliveries of gasoline are required to be made from drums carried on stake wagons. This method of delivery is inconvenient and uneconomical, and not without serious elements of danger, which will suggest themselves,—for example, the striking of the drums against each other on the wagon, the possibility of a drum being dropped to the street, the leakage which commonly occurs when a drum is opened, the failure at times to replace the bung in an empty drum containing explosive vapors and some residue-gasoline, etc.

This invention is accordingly directed to the provision of a novel type of tank truck, which will be entirely safe upon city streets and acceptable to city authorities. The tank of this truck preferably includes a plurality of compartments formed by partition walls and having individual discharge lines or pipes leading to a common delivery pipe, to which a hose may be connected. The individual pipes of the different compartments constitute the intake limbs of a siphon and in the siphon connection is provided a pump by which siphonic flow can be initiated. A by-pass around this pump is also provided to permit siphonic flow to continue, once it has been started. Associated with each compartment is a control valve and these valves are oper-

able selectively so that liquid from any selected compartment can be discharged at will siphonically, while the other compartments remain closed.

In addition to the above mentioned, I have illustrated an embodiment of the tank truck with which there is provided a complete fire fighting plant capable of being used to extinguish fires either on the truck or adjacent thereto.

The safety of the vehicle thus results from the construction of the tank, with its solid bottom and subdivisions, and its elevating delivery system, doing away with all bottom outlets and piping and faucets capable of being broken with resulting discharge of highly combustible liquid upon the streets, and all necessity for emergency valves, together with the active safeguarding agency afforded by the fire-fighting plant integrally connected with the tank and further provided with an external branch.

These and other features will become apparent as the specification proceeds, and it will naturally be understood that in some cases less than the complete, preferred combination of elements may be employed.

In the accompanying drawings forming a part hereof:

Fig. 1 is a side elevation of a tank truck embodying the invention, certain parts of the vehicle being incompletely shown;

Fig. 2 is a plan view, showing the delivery hose and fire-fighting hose brought out from the vehicle and with their intermediate portions broken away;

Fig. 3 is a vertical transverse section;

Fig. 4 is a plan view illustrating a mechanism for driving the compressor and the pump of the two systems on the truck from the power plant on the truck; and

Fig. 5 is a vertical transverse sectional view taken through one side of the tank vehicle, showing the delivery hose connected up to the fill pipe of an underground tank and the electric cable which grounds the vehicle tank and the hose to the underground tank in order to dissipate the static electricity that may be generated by the flow of the liquid.

Upon the vehicle frame 1 is mounted the longitudinally extending tank 2, cradled in bolsters 3. At opposite sides of the tank, on the ends of the bolsters, are running

110

boards 4, as usual, having railings or the like 5. The power plant of the truck is represented by the drive shaft 6 leading to the transmission case 7.

5 A power take-off 8, of familiar nature, projecting from the transmission case, drives a longitudinal shaft 9 containing universal joints, this shaft being bevel-geared to a transverse shaft 10 journaled in bearings on 10 a cross frame member 11, to drive by bevel gears another longitudinal shaft 12 adjacent one of the side walls. By this or equivalent gearing the power of the engine for driving the vehicle is utilized when the vehicle is 15 stationary for operating the two systems which will be described.

The tank 2 is divided by transverse partitions 13 into numerous separate equal compartments 2^a (five are shown) of unit capacity, most desirably two hundred gallons 20 each; and the bottoms, sides and ends of the tank and its compartments are entirely closed. Within the several compartments are vertical pipes or branches 14, having the 25 inlets 15 at their lower ends in pockets 15^a in the bottom, in order to insure full delivery of the contents of each compartment to the customers. The pipes 14 extend upward through the top of the tank, above 30 which they have lateral extensions 16, which are united to a longitudinal manifold pipe 17 running along the top of the tank at one side of the manhole domes 18 of the several compartments. Valves 19 in the extensions 35 16 enable any one of the branches 14 to be opened to the manifold, while the other branches remain shut off. Operating connections, represented schematically at 20 in Fig. 2, preferably extend from the valves 40 to the cab 21 or forward part of the vehicle, so that the valves may be operated from a convenient point.

The forward end of the manifold connects with the suction inlet of a pump 22 mounted 45 on a bracket 23 at the front of the tank, and from the discharge of this pump a fixed delivery pipe 24 extends downward at one side of the vehicle terminating at about the height of the under-frame in an out-turned 50 nozzle 25 formed for the reception of the hose coupling 26. The hose 27 attached to this coupling is equipped at its opposite end with a coupling 28 for the purpose of making tight screw connection with the upper 55 end of the fill pipe 29 of an underground tank. When the vehicle is traveling, the hose, which remains connected with the nozzle 25, is disposed upon the adjacent running-board or in other suitable manner on the 60 vehicle. A valve 30 in the lower part of the fixed pipe 24 enables the discharge of liquid to be shut off quickly in case of need.

An electric cable 31, preferably of bare copper wire, causes the tank, piping and hose 65 to be automatically grounded to the under-

ground tank when the hose is coupled thereto, so that any static electricity is drawn to earth as it is generated, and consequently can not accumulate to be discharged in a spark across any gap that might occur. One 70 end of this cable is permanently, or semi-permanently, connected at 32 to the nozzle 25 of the fixed delivery pipe 24, and the other end is clipped at 33 to the coupling 28 at the remote end of the hose. The cable 75 is preferably wound spirally about the hose, to keep it in place, but on detaching the clip 33 the hose may be removed, leaving the cable attached to the fixed pipe in readiness to be attached to a new hose. 80

A reservoir 34 containing fire-extinguishing compound is mounted on the vehicle frame at the front of the tank, and is kept under air-pressure supplied as needed by a compressor 35 connected by an air line 36 85 with the top of the interior of the reservoir. Piping 37 extends from near the bottom of the reservoir outward and upward to the top of the tank 2, where it passes longitudinally rearward at the opposite sides of the domes 18 from the manifold 17. This portion of the piping also constitutes a manifold, marked 38, which is connected with the upper parts of the interiors of the several tank compartments 2^a by short branches 39 which 90 are secured to openings in the sides of the domes. A readily accessible valve 40 at the outlet from the extinguisher reservoir is kept normally closed, and upon opening it the air space in the gasoline compartment can 95 be at once filled with flame-extinguishing froth or vapor, or liquid from the reservoir can be injected to float upon the surface of the gasoline. 100

The branch of the fire-fighting line which 105 extends upward to the top of the gasoline tank is equipped with a valve 41, which enables this part of the system to be shut off; and another branch 42, equipped with a similar valve 43, extends from the piping 37 110 to a hose-box 44 which is suspended below the running-board at the side adjacent to the group of control valves. The box is provided with side doors 45 and with a hose rack on which a small-diameter hose 46 is 115 coiled, the inlet end of this hose being constantly coupled to the end of the branch 42 within the box. In case of fire on the street or elsewhere outside of the vehicle, the fire-hose can be immediately pulled out of the box, the valves 40 and 43 being opened and the valve 41 closed, and the nozzle 47 on the end of the hose can be moved about as required to direct the fire-smothering stream upon the blaze. 120

The two systems for delivering the oil or gasoline and for extinguishing any fire that may arise therefrom, are preferably interconnected in the following manner: From the pipe 36 there extends a by-pass 130

pipe 48 to the piping 37, entering the latter above the valve 41. This by-pass is equipped with a shut-off valve 49, which is ordinarily closed. Another short pipe 50 connects the pipe 17 with the pipe 24, bypassing the pump 22, and also contains a normally closed valve 51. In event of failure of the pump, the valves 49 and 51 can be opened, the compressor being in operation, and this will admit compressed air to the top of the tank compartment whose valve 19 is open, the pressure being sufficient to elevate the oil or gasoline through the pipe 14, to run out through the piping 17 and 24. With a similar organization the pump 22 could be dispensed with entirely if desired. A valve 56 enables the pump to be shut off.

The pipes 14, 17, 24 and intermediate connections constitute a multiple siphon, of which the pipes 14 represent short, or intake, legs, while the pipe 24 and its hose represent the long, or delivery leg. When the siphon has been primed or started by means of the pump 22, the valve 51 in the by-pass 50 can be opened and the pump stopped, and the flow will then continue by virtue of gravity and atmospheric pressure.

30 The shaft 12, which has been referred to, bears two loose pulleys or drive elements 52 and 53 having clutch faces which can be engaged, either one or neither, by a double clutch element 54 slidably keyed to the shaft. The pulley 52 being belted to a pulley 55 on the compressor 35 and the pulley 53 to the pump 22, either of these pieces of apparatus can be driven from the power plant of the machine, and when the clutch is in neutral position both are at rest.

35 The pump 22 may be a measuring pump capable of being set to deliver any desired quantity of liquid and then stop, and to register on a counter the amount delivered. Such pumps are well-known. In that event less than two hundred gallon lots (if that be the capacity of each compartment) can be sold, or, with somewhat less safety, the 40 compartments might be larger or there might be only one tank interior.

45 This completes a description of the construction and mode of operation of a preferred embodiment of the invention, but I 50 wish it to be understood that I do not limit myself to the precise form and arrangement, and that various changes, omissions and substitutions may be made.

55 What I claim as new is:

60 1. In a tank-truck, the combination with the tank and delivery piping terminating in a hose connection, a hose attached to said connection and having a coupling at its far end, and a grounding cable connected at one end to the delivery piping on

the truck and at the opposite end detachably connected to the coupling on the far end of the hose.

2. A gasoline delivery vehicle having in combination multiple tank compartments 70 on the vehicle, pipes in the respective compartments constituting intake limbs of a siphon, a delivery limb on the vehicle, a pump connected in the siphon so as to be adapted to start the siphon flow from any 75 one of the compartments, and means for selecting the compartments.

3. A gasoline delivery vehicle having in combination multiple tank compartments 80 on the vehicle, pipes in the respective compartments constituting intake limbs of a siphon, a delivery limb on the vehicle, a pump connected with the siphon, means for bypassing the pump when flow has been established, and means for selecting the 85 compartments.

4. A gasoline delivery vehicle having in combination multiple tank compartments 90 on the vehicle, pipes in the respective compartments constituting intake limbs of a siphon, a delivery limb on the vehicle, a common pipe arranged to interconnect the several intake limbs with the delivery limb, selector valves interposed between said common pipe and the respective intake pipes, 95 and a pump connected in the siphon beyond said selector valves.

5. A gasoline delivery vehicle having in combination multiple tank compartments 100 on the vehicle, pipes in the respective compartments constituting intake limbs of a siphon, a delivery limb on the vehicle, a common pipe arranged to interconnect the several intake limbs with the delivery limb, selector valves interposed between said common pipe and the respective intake pipes, 105 a pump connected between said common pipe and the delivery limb, and means for bypassing the pump.

6. A gasoline delivery vehicle having multiple-tank compartments with pockets in their bottoms, pipes in the respective compartments having their intake ends in said pockets and constituting intake limbs of a siphon, a delivery limb on the vehicle, a 110 pump connected in the siphon so as to be adapted to start the siphon flow from any one of the compartments, and means for selecting the compartments.

7. A gasoline delivery vehicle having multiple-tank compartments of given capacity with pockets in their bottoms, pipes in the respective compartments having their intake ends in said pockets and constituting intake limbs of a siphon, a delivery limb on the vehicle, a common pipe interconnecting the several intake limbs and the delivery limb, selector valves interposed between said common pipe and the respective intake pipes, 115 a pump connected with the siphon be- 120

yond said selector valves, and means for bypassing the pump when flow has been established.

8. A tank vehicle having its tank body divided into a series of tank chambers of given capacity, with pockets in their bottoms, pipes mounted in the several chambers with their inlet ends in said pockets and thence extending upward through the top of the tank, external branches in continuation with said pipes turning downward at one side of the tank, valves for opening and closing said branches independently, a manifold pipe extending longitudinally of the tank body and connected with the several branches, a single outlet on the vehicle connected by a passage with the manifold pipe so as to form a siphon with any one of the inlet pipes, and piping forming a second passage connected between the manifold and the outlet and containing a pump for starting the siphonic flow.

9. A tank vehicle having its tank body divided into a series of tank chambers of given capacity, with pockets in their bottoms, pipes mounted in the several chambers with their inlet ends in said pockets and thence extending upward through the top of the tank, lateral branches in continuation with said pipes, valves for opening and closing said branches independently, a manifold pipe extending longitudinally of the tank body and connected with the several branches, a single outlet on the vehicle connected by a passage with the manifold pipe so as to form a siphon with any one of the inlet pipes, and piping forming a second passage connected between the manifold and the outlet and containing a pump for starting the siphonic flow.

10. A gasoline delivery vehicle having multiple-tank compartments, pipes in the respective compartments constituting intake limbs of a siphon, a delivery limb on the vehicle, and means interconnecting said intake limbs and the delivery limb, selector valves pertaining to the several tank compartments located in the upper parts of the siphon between the intake limbs and the delivery limb, and a pump on the vehicle adapted to start the siphonic flow from any one of the compartments.

11. The combination with a tank subdivided by partition plates into a plurality of compartments of a siphon in each compartment having means for interrupting the flow therethrough, mechanism by which said flow interrupting means may be remotely controlled, a common discharge pipe for said siphons, a pump for starting said siphons connected to said discharge pipe, and a bypass around said pump.

12. A liquid tank having a plurality of compartments, a discharge pipe for the tank connected to the several compartments, in-

dividual valves for controlling flow from the several compartments, remote control mechanism for said valves, siphon means for discharging the compartments, and means for initiating siphonic flow.

13. A liquid tank having a plurality of compartments, a discharge pipe for the tank connected to the several compartments, individual valves for controlling flow from the several compartments, siphon means for discharging the compartments, an outlet pipe from said siphon means, means in said outlet pipe for initiating siphonic flow, and a by-pass connected to said outlet pipe on each side of said means.

14. A liquid tank having a plurality of compartments, a discharge pipe for the tank connected to the several compartments, individual valves for controlling flow from the several compartments, remote control mechanism for said valves, siphon means for discharging the compartments, and a pump for initiating siphonic flow.

15. A vehicle carrying a liquid tank having a plurality of compartments formed by partitions in the tank, a discharge pipe for the tank connected to the several compartments, individual valves for controlling flow from the several compartments, siphon means for discharging the compartments, a pump for initiating siphonic flow, and a by-pass connection around the pump.

16. A liquid tank having a plurality of compartments, a discharge pipe for the tank connected to the several compartments, individual valves for controlling flow from the several compartments, siphon means for discharging the compartments, means for operating the valves selectively at a point remote therefrom, and means for initiating siphonic flow.

17. A liquid tank having a plurality of compartments, a discharge pipe for the tank connected to the several compartments, a valve associated with each compartment for controlling flow therefrom, means for controlling the valves selectively at a point remote therefrom whereby the valves may be opened one at a time, and means for initiating siphonic flow from the selected compartment.

18. A liquid tank comprising a tank body subdivided into a plurality of compartments in a line, a discharge pipe having an outlet at one end of the tank, a valve associated with each compartment for controlling flow therefrom, means operable from one end of the tank for operating the valves selectively, and means disposed at said end of the tank for initiating siphonic flow from a selected compartment.

19. A liquid tank comprising a tank body subdivided into a plurality of compartments in a line, a discharge pipe having an outlet at one end of the tank, a valve associated

with each compartment for controlling flow therefrom, means operable from one end of the tank for operating the valves selectively, siphon means for discharging the compartments, and a pump at said end of the tank for initiating siphonic flow.

20. A vehicle carrying as an integral part thereof a tank made up of a plurality of compartments, a siphon having a plurality of intake limbs terminating in different compartments and a single discharge limb, means for controlling flow from the individual compartments, and means connected to said discharge limb for initiating flow through the siphon.

21. A tank comprising a plurality of compartments, a siphon having a plurality of intake limbs terminating in different compartments, means for controlling flow from the individual compartments, selective mechanism for the control means operable at a point remote therefrom, and means for initiating flow through the siphon.

22. A tank comprising a plurality of compartments, a siphon having a plurality of intake limbs terminating in different compartments, valve means for controlling flow from the individual compartments, selective mechanism for said valve means operable at a point remote therefrom, and a pump for initiating flow through the siphon.

23. A tank comprising a plurality of compartments, a siphon having a plurality of intake limbs terminating in different compartments, means for selectively controlling flow from the individual compartments, said selective means being operable at a point remote from said valves, means for initiating flow through the siphon, and a by-pass around said means.

24. A vehicle carrying as an integral part

thereof a tank comprising a plurality of compartments, a common delivery pipe for the tank, means for initiating and maintaining siphonic flow from the compartments to the delivery pipe, and a plurality of selector valves interposed between the compartments and said means, said valves being independently operable at a point remote therefrom.

25. A vehicle carrying as an integral part thereof a tank made up of a plurality of compartments, a siphon having a plurality of intake limbs terminating in different compartments and a single discharge limb, and means for initiating flow through the siphon, said means being connected to the discharge limb.

26. The combination of a tank, vertical partitions therein dividing the tank into a plurality of compartments which have no openings therein except at the top, a pipe extending down into each compartment from the top thereof to a point near the bottom, a valve controlling the flow through each of said pipes and located above the level of the liquid in the compartment controlled by that valve when the compartment is full, means for discharging liquid from any compartment through said pipe thereof by siphon action, and a valve operating mechanism located outside the tank and operable to select any one of the said valves and operate the selected valve.

27. A liquid tank having a plurality of compartments, a discharge pipe for the tank connected to the several compartments, a valve associated with each compartment for controlling flow therefrom, remotely controllable means for operating the valves selectively, and a pump for initiating flow from the selected compartment.

FRED LAWRENCE HAYES.
